PUMP

Frederick E. Smith, Santa Paula, Calif.

Application April 28, 1941, Serial No. 390,652

2 Claims. (Cl. 128—297)

This invention relates to pumps.

An object of the invention is the provision of a novel form of pump which may be readily carried and be instantly serviceable for the removal of venom from a wound occasioned by snake bite or the sting of poisonous insects, such as spiders.

It is ordinary practice, in case of snake bite, to immediately make an incision and allow the blood to flow and drain the poison from the wound.

If a snake bite occurs in certain parts of the body, great difficulty is encountered if the wound is not readily accessible, such as on the back. Under such circumstances, suction cannot be applied to the wound by the mouth, and if the person who has the bite is alone, death may follow. The present invention contemplates a pump which may be readily applied to any portion of the body and exercise a powerful negative pressure upon the wound to remove the poisons therefrom. The device is so constituted that it may be locked in any position to constantly maintain a negative pressure and assure that all poison is removed and received within the said device. To assist the device, it is ordinary practice to cut the wound so that the poison is more readily removed.

An object of the invention is the provision of a pump of novel construction, positive in operation, readily useful, and generally superior to devices now known to the inventor for performing the function intended therefor.

With the above mentioned objects in view, the invention consists in the novel and useful provision, formation, construction, association, and relative arrangement of parts, members and features, all as shown in certain embodiments in the accompanying drawing, described generally, and more particularly pointed out in the claims.

In the drawing:

Figure 1 is an elevation of one form of the invention,

Figure 2 is a sectional view on the line 2—2 of Figure 1 and on an enlarged scale from said figure,

Figure 3 is a sectional view on the line 3—3 of Figure 2,

Figure 4 is a modified form of the invention, and,

Figure 5 is a sectional view on the line 5—5 of Figure 4.

Referring now to the construction of the improved pump shown in Figures 1 to 3, the same includes a cylinder 1 which is diametrically slotted for a portion thereof, as shown at 2 and 55

3, with the slotted portion thereof externally screw-threaded at one end, as shown at 4, to receive an internally threaded cap 5. The opposite end of the cylinder may be provided with an external ring 6 for the purpose of enhancing the appearance of the device, and likewise giving a larger surface contact with an object. Within the cylinder is a plunger designated generally as 7. This plunger includes a cup-type washer 8, the sides of which engage the inner surface of the cylinder, the cup-type washer embracing a cap 9 flanged at 10 to aid in guiding movement of the plunger within the cylinder. The cap and washer are held in working relationship by 15 a nut and screw arrangement 11 and 12. The cap 9 surrounds in part a plunger tube 13. Within the plunger tube is a coil spring 14. One end of the spring bears against a surface of the cap 9, and the opposite end against a disk 15 receivable within the confines of the plunger 2. A strut or rod 16 extends between the disk 15 and a disk 17, which is held against the slotted end of the cylinder through the medium of the cap 5. The end 18 of the plunger tube 13 is provided 20 with a pair of diametrically extended arms 19 and 20. These arms extend through the slots 2 and 3 and outwardly beyond the confines of the cylinder.

Loosely surrounding the cylinder 1 is a ring 21 provided with a pair of diametrically disposed wings 22 and 23, termed "finger bars." Secured between the wings or finger bars and the arms 19 and 20 are struts or rods 24 and 25. Thus, movement of the ring 21 relative to the cylinder 30 will produce movement of the plunger tube and plunger within the cylinder. This movement is not free, however, being opposed by spring 14, it being noted that the disk 15 is fixed against movement so that as the plunger tube moves upwardly to raise the plunger within the cylinder, the spring 14 is compressed between said disk 15 and the inner surface of the cap 9. Thus, the plunger and its tube are normally urged toward the entrance to said cylinder which is adjacent 35 the ring 6.

It has been found feasible and advantageous to provide some medium whereby the plunger may be locked or held in a fixed position within the said cylinder. To accomplish this, I have 40 provided, in one embodiment of my invention, a simple clutch which automatically releases to permit the plunger to move upwardly within the cylinder, and upon releasing the finger bars, to immediately hold the plunger at a defined position within the cylinder. In this manner, a con-

stant negative pressure is exerted upon an object when the ring end of the cylinder is in engagement with the object.

The clutch device includes a disk 26 provided with an enlarged opening 27, through which opening the rod 16 is passed. The disk 26 has an arm 28 extending laterally therefrom, then bent substantially at right angles to the lateral portion, as shown at 29, the end of the arm terminating in a clip 30, the clip comprising two short arms adapted to embrace sides of one of the struts or rods, in the present instance the one at 25. Thus, when the palm of the hand engages the end of the cap 5 and the fingers grip beneath the finger bars 22 and 23, pressure between the fingers and the palm of the hand will move the plunger and plunger tube upwardly within the cylinder, the rod 16 readily passing through the enlarged opening 27 of the disk 26. However, when the pressure between the palm of the hand and the fingers is released from engagement with the finger bars, and the plunger and plunger tube commence retrograde movement under force of the spring 14, the disk 26, particularly the wall bounding the opening, will engage the rod 16 and stop downward movement of the plunger. To release the plunger and plunger tube, the arm portion 29 may be engaged by the fingers to swing the same outwardly, as indicated in the full line position of Figure 2. The gripping position is that illustrated by the dotted lines in this figure.

The form of the invention illustrated in Figures 4 and 5 does not differ in any principal particulars from that shown in Figures 1 to 3, with the exception of the character of the locking device for the plunger and tube. In this instance, the cylinder adjacent the slots 2 and 3 is formed with a series of teeth 31 and 32. Thus, to lock the plunger in any selected position within the cylinder, the finger bars are rotated slightly to permit the arms 19 and 20 to enter between selected teeth.

The operation of the device is undoubtedly understood from the description given. However, in actual practice, and considering its use for snake bite, it has been deemed advisable to use a knife of some form to make an incision at the wound and apply the end of the pump over the wound. The plunger is then moved upwardly within the cylinder to exert a negative pressure upon the wound and attempt to remove the venom and prevent it from reaching the lymph channels. Instead of rapidly or slowly operating the plunger within the cylinder, it may be found advisable, in certain instances, to lock the plunger at a certain defined position within the cylinder so that a constant suction is applied over the wound.

The device has been found extremely compact

and useful in actual practice. The device is readily cleaned and sterilization does not affect the parts. All parts may be disassembled and readily reassembled. There is nothing to get out of order, and the device will stand rough usage.

In an embodiment of the invention, the same is constructed entirely of metal, heavily chromium plated to resist rust and prevent any deterioration by exposure to the elements.

It is quite apparent that the device may be used by either hand.

I claim:

1. A venom extractor of the suction type comprising a cylinder having closed and open ends with the closed end adapted to fit into the palm of the hand of the user, a hollow spring containing plunger in the cylinder, a stationary strut in alinement therewith over which the plunger is movable to compress the spring, said cylinder being axially slotted parallel with the strut, finger operated means to retract the plunger against spring tension including transverse bars engageable by the user's fingers, rods parallel with the cylinder and cross pieces extending through the slots and engaged with the plunger, and an angular clutch carried by said means having one leg extending through one of said slots and having an opening closely surrounding the strut with the other leg lying adjacent one of the rods and accessible to the fingers for clutch release whereby the plunger may be automatically locked in its furtherest retracted position to maintain a constant suction and manually released when desired.

2. A venom extractor of the suction type comprising a cylinder having closed and open ends with the closed end adapted to fit into the palm of the hand of the user, a hollow spring containing plunger in the cylinder, a stationary strut in alinement therewith over which the plunger is movable to compress the spring, said cylinder being axially slotted parallel with the strut, finger operated means to retract the plunger against spring tension including transverse bars engageable by the user's fingers, rods parallel with the cylinder and cross pieces extending through the slots and engaged with the plunger, an angular clutch carried by said means having one leg extending through one of said slots and having an opening closely surrounding the strut with the other leg lying adjacent one of the rods and accessible to the fingers for clutch release whereby the plunger may be automatically locked in its furtherest retracted position to maintain a constant suction and manually released when desired and a clip on the last mentioned leg of the clutch to embrace the sides of the strut.

FREDERICK E. SMITH.
